KEY RETAINER

Jack R. Shevin and David T. Shane, Chicago, Ill.

Application January 4, 1950, Serial No. 6,994

Term of patent 3½ years

(Cl. D17—14)

To all whom it may concern:

Be it known that we, Jack R. Shevin and David T. Shane, citizens of the United States, residing at Chicago, in the county of Cook and State of Illinois, have invented a new, original, and ornamental Design for a Key Retainer, of which the following is a specification, reference being had to the accompanying drawing, forming a part thereof.

Figure 1 is a front elevational view of a key retainer, showing our new design;

Figure 2 is a view looking from the right of Fig. 1; and

Fig. 3 is a perspective view of the key retainer.

We claim:

The ornamental design for a key retainer, as shown.

JACK R. SHEVIN.
DAVID T. SHANE.
